WATER DISPENSER

Roy Eugene Roberts, Cleburne, Tex., assignor to Rangaire
Corporation, a corporation of Texas

Filed Feb. 12, 1963, Ser. No. 73,530

Term of patent 14 years

(Cl. D67—4)

FIG. 1 is a left perspective view of a water dispenser showing my new design.

FIG. 2 is a right perspective view of the water dispenser.

FIG. 3 is a fragmentary cross section view taken along line 3—3 of FIG. 2.

The dominant features of my design reside in the portions shown in full lines.

I claim:

The ornamental design for a water dispenser substantially as shown and described.
